UNITED STATES PATENT OFFICE.

WILLIAM ROBINSON, OF BROOKLYN, NEW YORK.

ELECTRIC-RAILWAY SYSTEM.

No. 901,477.

Specification of Letters Patent.

Patented Oct. 20, 1908.

Original application filed July 20, 1904, Serial No. 217,297. Divided and this application filed October 5, 1904.
Serial No. 227,180.

To all whom it may concern:

Be it known that I, WILLIAM ROBINSON, a citizen of the United States, residing in Brooklyn, in the county of Kings and State of New York, have invented a new and Improved Electric-Railway System, of which the following is a specification.

My invention has reference to an electric railway safety system in which the "third rail" or contact conductor is divided into insulated sections normally disconnected from the source of working current.

My invention embodies various improvements in this connection, including an improved block signal system.

The nature of my invention will be understood from the description which follows, reference being had to the accompanying drawing, which forms a part of this specification, in which

Figure 1 is a diagram, showing the circuit instruments in elevation, partly in section, illustrating my invention; Fig. 2 is a section through the line x, x , Fig. 1, showing a fluid pressure valve with its magnetic control; Fig. 3 is a detached view of a circuit closer actuated by compressed air, with signals operatively connected thereto; Fig. 4 is a cross section through the line y, y , Fig. 1; Fig. 5 shows in elevation a modification of one of the circuit instruments illustrated in Fig. 1, and Fig. 6 shows an asbestos box with a fuse inclosed therein.

A, A' represent the service rails of a rail-road track, in which the rail line A is continuous and serves as a return for the electric currents, while the line A' is divided into sections, a, b, c , insulated from each other as shown at a', b', c' . The rail line A' is divided into insulated sections for signaling purposes, as hereinafter fully described.

B represents a working conductor, or third rail, parallel to the service rails and divided into sections d, e, f , separated or insulated from each other, as shown at d', e', f' .

C represents a high potential or working-current electric generator, and D a feed wire proceeding therefrom, while E represents another electric generator, of low potential current, and F a feed wire proceeding therefrom. The generators C and E , respectively, have one terminal connected by branch conductors g, g' , to the return rail A . Similar poles of said generators, the negative for instance, are, preferably, thus connected to said

return A . The high potential feed wire D is normally disconnected from the third rail sections d, e, f , as illustrated at h, i , Fig. 1. The low potential feed wire F , however, is normally connected to the third rail section f , for instance, through the wire k , armature lever l , coils of the magnet m and wire n .

A circuit instrument G or G' is connected to each third rail section, as shown. These instruments are connected by a valve p to the compressed air service pipe H , and said valves are controlled by the electro-magnets m, m' . The valves shown are of the type known as needle valves. The circuit instrument G is connected to the third rail section f , on which there is no car or train shown, consequently said instrument is in its normal condition, with the magnet m demagnetized, and as the valve stem q is pivotally or flexibly connected to the armature lever l , as shown at q' , the valve p is closed at p by the spring e' , thus shutting off air pressure from the cylinder r and leaving the working circuit normally open at h and i .

K represents a motor car or truck provided with the motor L arranged to drive the same. Said motor has one terminal connected to the axle or truck as shown at s ; the circuit continues thence through the wheels to the track rail A forming the return circuit, and the other terminal is connected to the controller M by the wire t , both in the usual way. The contact shoe or collecting brush u , supported by the truck and traveling in contact with the working or third rail conductor B , is electrically connected by the wire v to the rotating portion w , of the controller M , also in the usual way.

The circuit instrument G' is of precisely the same construction as the instrument G , described, but is here illustrated in the position assumed when in operation. The magnet m of said circuit instrument G' is connected by the wire n to the third rail section e .

The operation is as follows: When the car or truck K enters upon the section e the closing of the circuit by the controller M , carried by the car, closes circuit through the collecting shoe u , wire v , wire t , and motor L , to the axle and thence to the return rail A . This also closes circuit through the third rail section e , wire n , magnet m , armature lever l , to which one terminal, n' , of the magnet m is connected, and the wire k , to the low potential feed wire F . Thus the magnet m , at

tracting its armature, opens circuit at h' , thus switching off the low potential branch conductor k , and closes circuit at i' , through the high potential branch k' , whereby the 5 high potential or working current is substituted in the magnet m for the initial or low current from the feeder F . The object of switching off the branch wire k at h' , is to avoid the possibility of the high potential 10 current crossing and dominating the low potential or controlling current in the feeder F . To better insure this result, the circuit instrument G' is adjusted in such a way that the circuit is slightly opened at h' before being 15 closed at i' . This would tend to demagnetize the magnet m for an instant, thus interfering with the continuous magnetization of said magnet m and the desired result. To obviate this, however, I put additional spools 20 s' on the cores of the magnet m , and use an additional magnet r' arranged to attract an additional armature t' on the lever l . The coils of the magnet r' and the coils s' form one continuous closed circuit. Now when the 25 circuit is opened at h' through the magnet m , a counter current in the reverse direction is induced through the coils, s', r' , which latter attracts its armature t' , thus keeping the lever l in the position shown in the circuit. 30 instrument G' long enough to secure the remagnetization of the magnet m by the high potential current before the attractive force of the magnet r' has wholly died away. By the above means, it is evident, the possible 35 crossing of the high and low current conductors, in operation, is obviated.

When the magnet m attracts its armature, as shown in the instrument G' , it carries the valve-stem q downward, thus opening the 40 valve p at p' and closing the exhaust port at u' . This admits the compressed air to the cylinder r , forcing the piston r^2 downward, and, through the lever b^2 , actuates the knife blade switch h , closing the same. A 45 heavy resistance v' is put in the branch k' as it is only necessary to have sufficient current pass through this branch to actuate the magnet m . In like manner a light resistance w' is put in the branch d^2 in order to prevent 50 the complete short circuiting of the current from the branch k' and the magnet m .

It will be seen from the foregoing that the opening of the circuit by the controller M not only opens circuit through the motor L 55 but also through the magnet m , thus instantly reversing the valve p , shutting off the compressed air from the cylinder r , and opening the exhaust u' , and, simultaneously, the switch h . When the exhaust u' is 60 opened, the counter-weight c'' on the knife blade c^2 instantly forces the air out of the cylinder r , and swings said blade on its pivot d'' , opening the switch h . Thus the working current is cut off from the section e . 65 When, therefore, a motor car is coasting, or

stopped at a station, there is no working current in the third rail or contact section with which it is connected. When, however, the motor car passes from one section to another, to the section f , for instance, with the circuit through the controller M closed, the circuit instrument G is instantly brought into action in the manner just described in connection with the circuit instrument G' . The circuit instrument G is, in such case, brought 70 into action before the instrument G' is thrown out of action. The latter does not occur, in this case, until the collecting shoe u has wholly passed off the section e .

In Fig. 5 a lever l' is shown in addition to the armature lever l^2 , and is pivotally connected thereto by the insulated connection a^2 . By this arrangement of compound levers a greater opening of the circuit at the contact points i is secured than when a single lever is used. I use a slightly yielding spring e^2 85 back of one of the contact points i , which will allow a perfect electrical connection between said points without possible interference with a firm mechanical connection at 90 the valve seats of the valve p .

The stationary fuses a'' are placed in the branch conductors n or k , and the fuses b'' in the conductor d^2 at any convenient point between the third rail sections and the working feed wire D . These fuses are shown, in connection with the third rail section f , as located between the rails; while in connection with the section e they are located near the feed wires D and F . These fuses are intended to protect the car or train from burning in case of short circuiting, for instance when a car leaves the rails, making a short circuiting connection between the third rail section and the return rail. Such a short 105 circuit will blow out the fuse connected with that section, thus cutting off all current therefrom and from the car or train on said section. While these fuses may be located at any convenient point, I prefer to place 110 them some distance from the track, for instance near or at a station, but preferably on an isolated post, 76, or at a point somewhat remote from the track, by which means a short circuit on the track will cut off the 115 working current from the working section without even a flash or a flame of consequence in the vicinity of the car or train producing the short circuit, thus insuring safety to the train from fire, and to the passengers 120 from shock, and without interfering with the proper working of other sections of the track. The fuses a'' b'' are inclosed in asbestos boxes c''' , in order to prevent the blowing out of the fuse from setting fire to 125 any surrounding combustible material.

The block signal system herein disclosed is an embodiment of the Robinson electro-pneumatic system, embodying the closed circuit rail system for which a basic U. S. pat- 130

ent was granted to me on August 20, 1872, No. 130,661, (reissued July 7, 1874), the electro-pneumatic signal system disclosed in my British patent of August 30, 1871, No. 5 2280, the subject matter of both of which 10 patents is disclosed in my French patent of February 29, 1872, No. 94,393. The electro-pneumatic signal system disclosed in the above named patents is also disclosed in my 15 United States patent dated November 7, 1882, No. 267,259. As above indicated the block signal system herein described comprises the system described in my above 20 named patents, but modified and improved in a way adapting it for reliable and efficient use in connection with electric railroads of the sectional contact or third-rail type.

The signal circuits and connections will 25 be understood from the following description: 1 represents an electric generator of sufficient strength to operate the signal-controlling magnets with which it is connected. One terminal, the positive, is connected by 30 the wire 2, to the return rail A, while the opposite terminal, the negative, is connected by the wire 3 to the feed wire 4. The signals 5 and 6 are of the compressed air or fluid-pressure type and identical in construction. The signal 5 is illustrated as in its normal or safety position, while the signal 6 is represented as in its operative or danger position. The signals 5, 6, are actuated by compressed air derived from the compressed 35 air pipe 7, through the needle valves 8, which control the admission of compressed air to the actuating mechanism of said signals. Said valves are controlled by the electro-magnets 9. When the magnet 9 is 40 magnetized, as shown in connection with the signal 5, it attracts its armature 10, which is connected to the valve stem 11, thus carrying said valve stem downward, closing the exhaust port as shown at 12, and opening 45 the valve at 13, thus admitting the compressed air from the pipe 7 through the valve 8 to the cylinder 14. The compressed air entering said cylinder instantly forces the piston 15 downward, thus turning the 50 lever 16, connected thereto, on its pivot 22. This forces upward the rod 17, which is connected to the signal mechanism at 18, thus turning the signal on its pivot 19, and forcing it into the safety position as illustrated in the signal 5. When the magnet 9 is 55 demagnetized the spring 23 closes the valve at 13 and opens the exhaust at 12, thus allowing the compressed air to escape from the cylinder 14. The counter-weight 21 of 60 the signal now swings the signal blade 20 into a horizontal position, the danger position, as shown in connection with the signal 6.

It will be understood that the motive 65 power is used to keep the signal in a position

indicating safety, whereas the absence from the signal of the motive power, that is, of the controlling electric current or the fluid pressure, results in the counter-weight 21 swinging the signal into a position indicating danger. Thus any error which might occur through negligence or otherwise, would be on the side of safety, since an error, as indicated, might possibly result in giving a danger signal when there was no danger, 75 but could not result in giving a safety signal when there might be danger.

I will now describe fully the signal circuits.

The current from the generator 1 is 80 divided in multiple between the rail sections *a*, *b*, *c*, and the magnets of the signals 5, 6 &c. Thus, from the conductor 24 connected to the feeder 4, the wire 25 leads to the track section *a*, and the wire 26 to the signal magnet 9 of the signal 6. The resistance 27 is introduced between the conductor 24 and the track section *a* in order to equalize, or properly differentiate, the current between said track section and the said signal magnet. In 85 like manner the feeder 4 is connected to the track section *b* through the conductor 28 and the wire 29, and to the signal magnet 9 of the signal 5, by the wire 30. The resistance 31 is inserted in the wire 29, between 90 the conductor 28 and the track section *b*. In like manner also the feeder 4 is connected to the rail section *c* through the conductor 32 and the wire 33 and to a signal magnet, not shown, by the wire 34. The resistances 31 95 and 35 are introduced in the wires 29 and 33 to regulate the strength of current delivered, respectively, to the rail sections *b* and *c*, as already explained in connection with the rail section *a*.

Referring now to the track section *c*: The current from the feeder 4 passes through the wire 33, the rail section *c*, the relay magnet 36, the wire 37, return rail A, and the wire 2 to the generator 1, thus completing the 100 circuit. There is no car or obstruction shown on the section *c*, therefore the relay 36 remains magnetized, attracting its armature 38 and keeping the circuit of the magnet 9 of the signal 5 closed at the contact 105 points 48, whereby said signal is kept by its motive power normally in a position indicating safety, as already described. The train or car K, however, has entered upon the track section *b*. The current, therefore, passing normally through the wire 29 and the rail section *b* to the relay magnet 40 is short-circuited from said magnet by the wheels and axles of the car K. The relay magnet 40 being thus demagnetized releases its 110 armature 49, thus opening circuit through the magnet 9 of the signal 6, whereby the signal 6 is swung into a position of danger, as 115 already described. That is, the signal 6 becomes a perfect block signal for the protec- 120 125 130

tion of the train or car K while it is on the block or section b.

When an electric train is on a section or block, as described, and not using working current, it must be either at a standstill or coasting. In either case the wheels and axles short circuit the current from the relay and the signals operate perfectly, as described.

When, however, a heavy electric train is running over a section under a pressure of perhaps eight or ten hundred volts it is conceivable that a leakage from this heavy working current might, under some circumstances, reach the relays 36 or 40, magnetizing the same and thus displaying a false or safety signal while the section was actually blocked by the presence of the train. I obviate such a possibility in a simple manner.

Referring to Figs. 1 and 4: It has been pointed out that the circuit instrument G, which controls the admission of working current to the third rail section f, is shown in its normal inert condition, with its armature lever l released. The insulating plug 45, secured to said lever, is thus brought down upon the spring clip 44 (see Fig. 4), pressing it down upon the contact post 43, thus closing circuit between the wires 41

and 42 of the circuit through the signal magnet 9 of the signal 5. That is, the circuit of said magnet is now normally closed at two independent contact points, and by two independent instruments, namely, at the contact points 47 just described, by the inert circuit instrument G, and at the contact points 48 by the energized relay magnet 36. Thus the signal magnet 9 is energized and the signal 5 kept in a position indicating

safety while the section or block e, f, is clear and in a safe condition for the reception of a train. When, however, a car or train K occupies the section b and is using working current, the magnet m of the circuit instrument G' is necessarily energized, as described, and, attracting its armature l, opens circuit at the contact points 47, between the wires 41 and 42 of the circuit of the magnet 9 of the signal 6. At the same time the relay 40, being deenergized by the short-circuiting action of the wheels and axles of the car or train, opens circuit at the contact points 48 in the circuit of the same signal magnet 9. Thus the circuit of said magnet

9 is open at the two points 47 and 48, and the signal 6 is swung into the danger position by its counter-weight 21, and remains there, as illustrated. Now, suppose that an errant current for any reason reaches the relay magnet 40 and magnetizes the same, thus closing the circuit of the signal magnet at the point 48. Manifestly this cannot affect the danger position of the signal 6, for the reason that the circuit of the signal-controlling magnet 9 is still open at the point

47. It is evident, therefore, that while the car or train K occupies a section or block, and is using working current, it is immaterial whether the relay magnet 40 is magnetized or not, since its magnetization cannot remove the signal 6 from the danger position.

Let us assume now that the circuit is opened through the controller M. This not only cuts off the current from the motor L, but also from the magnet m of the circuit instrument G', as already described, thus leaving the car K on the section b without working current, and therefore, of course, without possibility of any wandering current reaching the relay 40. The wheels and axles of the car K, therefore, under these conditions, short-circuit the current from the relay 40 with certainty, thus demagnetizing the same and keeping the magnet 9 of the signal 6 demagnetized and said signal in a position of danger. Thus, it is evident that the block signal 6 will remain exposed in a position of danger as long as there is a car, or train, or a single pair of wheels with their axle, or a short-circuiting connection of any kind, between the section b and the return rail A, whether said car or train be using working current or not.

I prefer to make the main circuit closing part of the circuit instrument G itself in the form of a danger signal to indicate at a glance to all concerned whether the working current is actually connected to the third rail section controlled by said instrument or not. This construction is shown in Fig. 3 in which G² represents the apparatus illustrated, in which the blade c² is enlarged and its counter-weight c'' provided with a colored signal glass 50 which when the working circuit is closed at h, is swung into position in front of the lamp glass 51. Thus at night the colored light will indicate that the working current is actually connected to the third rail section, and that the same is therefore dangerous to be touched. The white light 51 will indicate positively that there is no working current in the third rail section, since the light cannot show white if the working circuit is closed at h, and the colored glass 50 thus moved in front of the white light at 51. In the day-time the position of the blade c² or of the counter-weight c'' will indicate to workmen and others whether the third rail section is actually in a dangerous condition or not.

The cross section, Fig. 3, shows the blade c² of the circuit instrument insulated by the insulator 52 from its supporting shaft d'', and, in like manner, the connecting rod 53 is insulated by the insulation 54 from the lever b² (see Fig. 1). Thus the blade c² is fully insulated from its supporting post or stand 55, and consequently, when the blade c² closes circuit between the spring clips at h the cur-

rent therefrom cannot escape beyond said insulation.

It is evident that the particular form of the circuit closer shown in Fig. 3, so far as closing circuit is concerned, is not material so long as it is arranged to properly open and close the circuit described. In Fig. 3 the counter-weight c' is provided with the insulating plug 57, which, when the main circuit is opened at h , presses the spring clip 58 down upon the post 59, thus closing circuit between said clip and post. Thus the lever 60, constituting the signal blade and its counter-weight, may, in its normal inert condition, close the signal circuit between the wires 41, 42, already described as closed by the armature lever l ; or said lever 60 may open and close circuit at 58, 59, as illustrated, from the feeder F, through the wires 68, 69, 70 the magnet 70, the wire 74, and the return rail A, thus closing circuit and controlling an additional or special signal 71, at a station or elsewhere, in advance or rearwardly, to indicate at distant points the exact open 25 position of the lever 60, and consequently the safe condition of the contact section with which the circuit instrument G^2 is connected. In like manner also, it will be understood that when the lever 60 is in position, 30 closing the working circuit at h , it may also be made to close a supplementary circuit to indicate at a distant point the positive danger position of said lever 60. When the circuit at h is thus closed the insulating plug 62, 35 with which said lever 60 is provided, presses the spring clip 63 against the fixture 64, thus closing the supplemental circuit from the feeder F through the wires 68, 65 and 66, the signal-controlling magnet 72 and the 40 wire 75 to the return rail A, thus completing the circuit and bringing the signal 73 into a position indicating danger.

It will be understood that the magnet 72 actuates and controls the signal 73, located 45 at any desired point, in a station or elsewhere, in any direction from said circuit closer, thus indicating positively at a distance the closed or danger position of the lever 60, and consequently the live and dangerous condition of the contact section with which it is connected.

The signals 71, 73, are of any suitable or conventional construction; and the term "lever 60" is intended to indicate the movable circuit-closing member, of any suitable construction, of the circuit instrument G^2 . It is evident that the open position of the lever 60 may, preferably, be caused to open circuit at 58, 59, through the magnet 70, 55 thus causing the counterweight of the signal 71 to bring the same by gravity into a position indicating the "dead section" condition of the third rail. And, in like manner, also, the closed position of the lever 60 may 60 be caused to open circuit at 63, 64, thus de-

magnetizing the signal magnet 72, and bringing the signal 73 into the "alive section" position, by gravity. These are details, the importance of which is readily understood by any one skilled in the art. The armature levers l are reversed in the usual way by the springs l^2 , or by the valve springs e'' , and the armature levers 38, 49, are reversed by the springs 61.

It will be understood that the signal circuits herein described are equally applicable to an electro-pneumatic or to an electro-mechanical signal system, or to any system controlled or operated electrically, and in connection with any suitable switch or means 80 arranged to control the connection of the working current to sectional contacts of an electric railway.

Resistances 67 are inserted in the signal circuits as required by conditions.

The air tank T, and the air apparatus generally, is kept supplied with any desired pressure by means of air compressors operated by stationary power, or by the action of passing trains, and as many auxiliary air 90 tanks as necessary are used, connected in any suitable manner with the primary tank or compressor system.

Having thus described my invention, what I claim as new and desire to secure by Letters Patent, is—

1. In an electric signal system for railroads, comprising a closed rail circuit, a relay magnet forming a part thereof, a secondary circuit under control of said relay 100 magnet, the combination therewith of an electric railway system comprising a working conductor formed in sections insulated or separated from one another, a power current feeder arranged for connection to, and disconnection from, said sections, and means for opening and closing the signal circuit independently of said relay magnet.

2. The combination, with a railroad signal system comprising a continuously closed rail circuit, a relay magnet connected thereto, and a signal controlled by a magnet included in a circuit under control of said relay, in combination with an electric railway system embodying a working conductor 110 formed in sections insulated or separated from each other, a power current feeder normally disconnected from said sections, means for connecting said feeder automatically to said sections, and means for opening and closing the signal circuit independently of said relay.

3. The combination with a railroad signal system comprising a continuously closed rail circuit, a relay magnet forming a part thereof, and a signal controlled by a magnet included in a circuit under control of said relay, of an electric railway system embodying a working conductor formed in independent sections, a power current feeder 125

normally disconnected therefrom, means for connecting said feeder to said respective sections, and an additional magnet arranged to open and close the circuit of said signal 5 independently of said relay.

4. The combination, with a signal system for railroads, comprising a continuously closed rail circuit, a relay magnet included therein, and a signal actuated by fluid pressure 10 controlled by a magnet included in a circuit under control of said relay, of means for automatically opening and closing said last named circuit, independently of said relay.

15 5. An electrically controlled signal system for railroads, embodying a closed track circuit and arranged for operation and control by passing trains, in combination with an electric railway system having sectional 20 working conductors normally disconnected from the source of propulsion current supply, and a return circuit common to the propulsion current and the signal controlling current, means for operating said signal system 25 automatically, and means for preventing the accession of operative propulsion current to the signal controlling magnets.

6. An electrically controlled signal system for railroads, embodying a closed track circuit and arranged for operation and control by passing trains, in combination with an electric railway system embodying a working conductor made in sections, a power current feeder normally disconnected from said 30 sections, a return circuit common to the propulsion and the signal controlling currents, and means for operating said signal system automatically without liability to interference from the power current.

35 7. An electrically controlled signal system for railroads, embodying a closed track circuit, a relay connected thereto, and a signal-controlling circuit under control of said relay, in combination with an electric railway system comprising a working conductor formed in sections, insulated or separated from one another, a power current feeder normally disconnected from said sections, means for connecting the same thereto, 40 means for operating said signal system under electric trains, and means for preventing the encroachment of operative power current upon the signal controlling magnets.

8. An electrically controlled fluid pressure signal system for railroads, arranged for 45 operation and control by passing trains and embodying a closed track circuit, in combination with an electric railway system having a working conductor formed in sections separated or insulated from one another, a power current feeder normally disconnected from said sections, means for connecting said feeder to said sections and disconnecting the same therefrom, a return conductor, means for 50 operating said signal system automatically, and means for preventing the accession of operative power current to the signal controlling magnets.

55 ically, and means for preventing the accession of operative power current to the signal controlling magnets.

9. An electrically controlled fluid pressure signal system for railroads, arranged for 60 operation and control by passing trains, and comprising a closed track circuit and a relay connected thereto, in combination with an electric railway system comprising a working conductor formed in sections separated 65 or insulated from one another, a return rail circuit, a power current feeder normally disconnected from said sections, means for connecting said feeder thereto, means for operating said signal system automatically, and means for preventing the encroachment of 70 said power current upon said relay.

10. An automatic, electrically controlled, fluid pressure signal system for railroads, embodying a closed track circuit, a relay 75 connected thereto, an additional circuit under control of said relay, and a magnet therein for controlling the operation of said signal, in combination with an electric railway system comprising sectional contact 80 conductors, a power current feeder normally disconnected therefrom, means for automatically connecting said feeder to said sections, a return rail circuit common to the power and signal controlling currents, and means 85 for operating said signal system under electric trains without interference from the power current.

11. An electrically controlled fluid pressure signal system for railroads, arranged 90 for operation and control by passing trains, and embodying closed track circuits, relays connected thereto, said relays controlling circuits for actuating said signals, in combination with an electric railway system 95 having sectional contact conductors, a power current feeder normally disconnected therefrom, a return rail circuit, means for operating said signal system automatically, and means for preventing the encroachment of 100 power current upon the signal controlling magnets.

12. An electrically controlled signal for railroads, arranged for operation and control by passing cars or trains, and comprising a closed track circuit, a relay connected thereto, a signal-controlling magnet in a circuit under control of said relay, in combination with an electric railway system having sectional contact conductors and a return rail circuit, and a circuit instrument under control of the car or train and arranged to open the signal circuit when the car or train is using propulsion current.

13. The combination, with a signal system 125 for railroads, comprising a closed rail circuit, a relay magnet forming a part thereof, a signal-controlling magnet included in a circuit under control of said relay, of an electric railway system comprising a sec- 130

tional working conductor, a power current feeder normally disconnected therefrom, means for connecting said feeder to the respective sections of said working conductor, 5 and means for opening and closing the signal circuit at a plurality of independent points, through independent instrumentalities.

14. An electrically controlled signal system for railroads, embodying a closed track circuit, a relay connected thereto, and a signal-controlling circuit under control of said relay, in combination with an electric railway system comprising a working conductor 10 formed in sections insulated or separated from one another, a power current feeder normally disconnected from said sections, means for automatically connecting said feeder to said sections and disconnecting the same therefrom, an identical track return circuit for both the signal relay current and the power current, and means for preventing the power current from interfering with the proper operation of the signal system. 20

15. In an electric railway and signal system, the combination with a working conductor, a feeder carrying working current and normally disconnected from said working conductor, a traction rail return for said 25 working current, and a circuit instrument actuated and controlled by current from a stationary source of current supply and arranged to connect said feeder to said working conductor and to disconnect the same 30 therefrom, of a signal arranged to show the open or closed position of said circuit instrument with reference to said working current feeder. 35

16. The combination, with an electric railway system embodying a working conductor formed in sections insulated or separated from each other, a working current feeder normally disconnected from said sections, a traction rail return for said working current, 40 and circuit instruments actuated by current from a stationary source of current supply 45

and arranged to connect said feeder to the respective sections of said working conductor, and to disconnect the same therefrom, of electrically controlled visual or 50 semaphore signals under control of said circuit instruments, and arranged to indicate whether said working current feeder is or is not connected to the respective working sections with which said circuit instruments, 55 respectively, are connected.

17. The combination with an electric railway system having a working conductor, a feeder carrying working current and normally disconnected from said working conductor, a traction rail return for the working current, and a circuit instrument deriving operative current from a stationary source of current supply and arranged to connect said feeder to said working conductor and to disconnect the same therefrom, 60 of an electrically controlled signal connected to said circuit instrument, and arranged to indicate safety when said circuit instrument is in its normal condition disconnecting said 65 working current feeder from said working conductor. 70

18. The combination, with an electric railway system embodying a sectional working conductor, a working current feeder normally disconnected therefrom, a traction rail return for the working current, and a circuit instrument deriving operative current from a stationary source of current supply and arranged to connect said feeder to 75 said working conductor and to disconnect the same therefrom, of a signal connected to said circuit instrument and arranged to indicate the live and dangerous condition of the working conductor section with which it 80 is connected, when said circuit instrument is in position connecting said working current feeder to said working conductor. 85

WILLIAM ROBINSON.
